[57] **CLAIM**

The ornamental design for an aircraft flap hinge cover,
as shown and described.

DESCRIPTION

FIG. 1 is a perspective view of an aircraft flap hinge
cover showing my new design.

FIG. 2 is a top plan view thereof.

FIG. 3 is a bottom plan view thereof.

FIG. 4 is a side elevation view, the side not shown being
a mirror image thereof.

FIG. 5 is a left end elevation view.

FIG. 6 is a right end elevation view.

FIG. 1**FIG. 6****FIG. 2****FIG. 3****FIG. 4****FIG. 5**
